Primary Examiner — Richard Edgar*Assistant Examiner* — Jessica Ruth Grable(74) *Attorney, Agent, or Firm* — Li & Cai Intellectual Property (USA) Office(57) **CLAIM**

The ornamental design for a garment rack as shown and described.

DESCRIPTION

FIG. 1 is a top, front, right side perspective view of a garment rack, showing the claimed design;

FIG. 2 is a front elevation view thereof, the rear view being a mirror image of the front view;

FIG. 3 is a left side elevation view thereof;

FIG. 4 is a right side elevation view thereof;

FIG. 5 is a top plan view thereof;

FIG. 6 is a bottom plan view thereof; and

FIG. 7 is an enlarged view of portion 7 of FIG. 1; and,

FIG. 8 is an enlarged view of portion 8 of FIG. 1.

The broken line shown in the drawings is included for the purpose of illustrating areas of enlargement and forms no part of the claimed design.

1 Claim, 6 Drawing Sheets
